SPARE TIRE BRACKET

Daniel N. Davis, 260 S. Grove St., Denver, Colo.

Filed Jan. 15, 1965, Ser. No. 83,451

Term of patent 3½ years

(Cl. D54—1)

FIG. 1.

FIG. 2.

FIG. 3.

FIG. 4.

FIGURE 1 is a perspective view looking down and to the left at the spare tire bracket incorporating my new design;

FIGURE 2 is a left-side elevational view of the bracket showing the hinged tire-carrying element raised into its upper position and with portions of the near strut broken away to reveal the mounting studs;

FIGURE 3 is a front elevational view showing the hinged tire-carrying element in its lower position as in FIGURE 1; and,

FIGURE 4 is a rear elevation having portions of the tire-carrying element broken away to conserve space.

I claim:

The ornamental design for a spare tire bracket, as shown and described.
